ABSTRACT

A new variety of *Gentiana L.* plant (Japanese gentian) which is a double flower type and has about 3 (2.9 on average) side shoots with only one node.

4 Drawing Sheets

1

Common name: Japanese gentian.

Botanical classification: *Gentiana L. hybrid*.

Varietal denomination: 'Ashiro 29-2076'.

BACKGROUND OF THE NEW VARIETY

The present invention relates to a new and distinct variety of Japanese gentian, *Gentiana L.*, which has been given the variety denomination 'Ashiro 29-2076'.

This new gentian is a double flower type and has about 3 (2.9 on average) side shoots with only one node. It is adapted for use as cut flowers or pot flowers.

ORIGIN OF THE VARIETY

The variety resulted from a multiple-step cross-breeding program starting from a group of unpatented varieties. The ancestor varieties were unpatented strains owned by the applicant, having the company-internal names: '17INP' which belongs to the species *Gentiana triflora*, and '25-322-R1', '26-904', '12-320-1', '14-526-2', '11-24-1', '11-192-1', '13SH', '10-76', '6-62', '12-186-1', '12-212-1', and '25-817', which belong to the species *Gentiana scabra*. Group crosses and/or self-crosses with a single individual were performed. The program had seven steps, as shown in the map of FIG. 6, which also indicates the company-internal names of the intermediary, unpatented strains. At each step, the individuals with good plant and flower shape were selected. The corresponding species identification is

((scabra (scabra x triflora))x scabra))x
((scabra x (scabra x triflora)).

The multiple-step cross-breeding program was performed over multiple growing seasons up to 2018; in October 2018, selection of the variety was performed. We asexually reproduced the variety by vegetative reproduction through cuttings, tissue culturing via lateral bud culture, and in October 2020, the new variety was found to be stable and asexually reproduced true to type in successive generations.

2

The variety was developed and propagated in Iwate, Japan.

The variety can be propagated by cutting (optimal timing is mid-February) and/or tissue culturing via lateral bud culture.

Cultivation of the variety does not require particular conditions. Maintenance and storage method of the plant material can be by tissue culture via lateral bud culture.

The variety is adapted for use as cut flowers or pot flowers.

SUMMARY OF THE VARIETY

The variety is distinguished by double flower type and has about 3 (2.9 on average) side shoots with only one node, as compared to 'Shine Blue Ashiro' variety which is single flower type and has about 6 side shoots with only one node. 'Shine Blue Ashiro' is unpatented.

A comparison with 'Shine Blue Ashiro' variety is presented as follows in Table 1:

TABLE 1

	'Shine Blue Ashiro'	'Ashiro 29-2076'
25 Flower type	Single	double
Number of side shoots with only one node	6	about 3 (2.9 on average)

Additional distinguishing characteristics of the 'Ashiro 29-2076' plant are the about sept (6.8 on average) lobes of the paracorolla.

BRIEF DESCRIPTION OF THE DRAWINGS

In the accompanying drawings, which are as nearly true as is reasonable possible to make in a color illustration of this type:

FIG. 1 is a color photograph showing the 'Ashiro 29-2076' plant as grown in a culturing bed;

FIG. 2 is a color photograph showing flowers of the 'Ashiro 29-2076' plant;

FIG. 3 is a color photograph showing flowering stages of flowers of the 'Ashiro 29-2076' plant;

FIG. 4 is a color photograph showing petals of flowers of the 'Ashiro 29-2076' plant;

FIG. 5 is another color photograph showing flowers of the 'Ashiro 29-2076' plant;

FIG. 6 is a map showing the steps of the cross-breeding program from which the variety was obtained.

Due to chemical and/or digital development, processing and printing, the plants or portions of plants depicted in the photographs may or may not be precisely accurate, when compared to the actual botanical specimens.

DETAILED DESCRIPTION OF THE INVENTION

The plants in the botanical description below and shown in the Figures were grown in Iwate, Japan. The plants were collected in October 2020 at age 16 months.

Colors are given according to The 2015 R.H.S. Colour Chart.

BOTANICAL DESCRIPTION

TABLE 2

Stem	Length:	74.5 cm	20	Inflorescence Plant:	Distribution of flowers:	clustered
	Stem shape in cross-section:	circular			Position of flowers:	terminal and axillary
	Thickness (main flowering stem):	3.8 mm			Number of terminal flowers (average):	6.7
	Number of flowering stems per plant (average):	12.7			Typical plant height:	about 74.5 cm (cut flower or potted plant)
	Texture:	smooth			Typical growth habit:	erect
	Color:	strong yellow green (145A on RHS Colour Chart)			Plant spread (average):	65.0 cm
	Anthocyanin coloration at two thirds from base:	present			Sequence of flowering:	from top downwards
	Number of internodes longer than 5 mm (average):	20.4			Number of flowers per inflorescence:	top: 6.7 others: 1.9
	Length of internode in central third:	3.8 cm			Sequence of flowering:	from top downwards
	Side shoots:	present			Number of flowers at central flowering node (average):	1.9
Leaf	Number of side shoots with only one node (average):	2.9			Number of flowering node:	6.5
	Number of side shoots with more than one node (average):	11.6			Shape of bud:	narrow oval
	Position of longest leaf:	in lower third			Length of bud (average):	42.51 mm
	Length:	9.0 cm			Diameter of bud (average):	13.94 mm
	Leaf arrangement:	opposite leaf arrangement			Color of bud:	dark purple (83A on RHS Colour Chart)
	Leaf attachment:	sessile			Type:	double
	Leaf apex:	broad lanceolate			Time of flowering:	late October
	Leaf margin:	entire			Depth:	41.7 mm
	Leaf base:	rounded			Diameter at middle third:	17.7 mm
	Leaf texture (inner side):	smooth			Shape:	campanulate
Leaf	Leaf texture (outer side):	smooth			Diameter at top:	28.5 mm
	Leaf color (inner side):	moderate olive green (137A on RHS Colour Chart)			Curvature of lobes:	strongly reflexed
	Leaf color (outer side):	moderate yellow green (138C on RHS Colour Chart)			Color of inner side of lobes:	strong blue (N95B on RHS Colour Chart)
	Leaf venation pattern:	parallel venation (three lines)			Tube length (average):	27.1 mm
	Width:	1.9 cm			Color of upper part of inner side of tube:	strong purplish blue (95C on RHS Colour Chart)
	Shape:	broad lanceolate			Color of upper part of outer side of tube:	dark purple (83A on RHS Colour Chart)
	Shape in cross section:	folded upwards			Streaked pattern on outer side of tube:	present
	Shape in longitudinal section:	straight			Color of streaked pattern on outer side of tube:	dark purple (83A on RHS Colour Chart)
	Twisting:	absent			Density of spots on the inner side of the corolla lobes:	sparse
	Number of conspicuous veins:	3			Density of spots on the upper part of the inner side of the corolla tube:	medium
Leaf	Anthocyanin coloration:	present			Density of spots on the outer side of the corolla tube:	absent
	Paracorolla:				Number of lobes:	6.8
	Calyx:				Length of lobes:	8.7 mm
	Paracorolla:				Width of lobes:	10.5 mm
	Calyx:				Shape of lobes:	broad triangular
	Paracorolla:				Shape of distal end of lobes:	acute
	Calyx:				Presence of secondary lobes:	present
	Paracorolla:				Average number of secondary lobes per flower:	6.8
	Calyx:				Shape of secondary lobe apex:	acute
	Paracorolla:				Presence of paracorolla:	present
Leaf	Paracorolla:				Number of paracorolla lobes (average):	6.8
	Calyx:				Paracorolla apex shape:	acute
	Paracorolla:				Anthocyanin coloration:	present
	Calyx:				Length of tube:	15.3 mm
	Paracorolla:				Diameter of tube:	6.0 mm
	Calyx:				Shape of tube:	funnel-shaped
	Paracorolla:				Shape of lobe:	narrow lanceolate
	Calyx:					
	Paracorolla:					
	Calyx:					

TABLE 2-continued

US PP35,012 P2

5

TABLE 2-continued

Sepal	Sepal number:	6
	Sepal lobe shape:	narrow lanceolate
	Sepal apex:	acute
	Sepal color (inner side):	dark yellowish green (136B on the RHS Colour Chart)
	Sepal color (outer side):	strong yellow green (143C on the RHS Colour Chart)
Reproductive organs	Stamens and anther:	stamens are mutated into petals and there is no anther
	Time of flowering:	late October
	Pistil number:	1
	Pistil length (average):	38.3 mm
	Anther shape:	narrow oval
	Anther color:	light yellow green (145C on RHS Colour Chart)

6

In the above chart, specific numbers correspond to average values.

Other features of the plant are as follows:

Disease resistance.—Normal resistance was observed for pests and diseases in Iwate, Japan, using pest control by chemical spraying for gentian.

Cold hardness.—Strong, the variety can withstand winter in Iwate, Japan, including low temperatures of about -10° C. with abundant snow.

Heat tolerance.—Normal, the variety can withstand summer in Iwate, Japan, including high temperatures of about 35° C.

Flower fragrance.—Absent.

We claim:

1. A new and distinct variety of *Gentiana* plant named 'Ashiro 29-2076', substantially as described and illustrated herein.
